UNITED STATES PATENT OFFICE.

JOHN PRINCE, OF KANSAS CITY, MISSOURI, ASSIGNOR TO THE STEWART SAND COMPANY, OF KANSAS CITY, MISSOURI, A CORPORATION OF MISSOURI.

DESIGN FOR A SIGN.

56,765.

Specification for Design. Patented Dec. 14, 1920.

Application filed January 19, 1920. Serial No. 352,631. Term of patent 7 years.

To all whom it may concern:

Be it known that I, JOHN PRINCE, a citizen of the United States, residing at Kansas City, in the county of Jackson and State of Missouri, have invented a new, original, and ornamental Design for a Sign, of which the following is a specification, reference being had to the accompanying drawing, forming part thereof.

The figure is a plan view of the design.

The design consists of an elongated, rectangular panel 1, having an outer field 2 of drab, an inner field 3 of green and an intermediate separating strip 4 of black, the field 3 and the band or strip 4 being oblong.

I claim:

The ornamental design for a sign, as shown and described.

JOHN PRINCE.
